UNITED STATES PATENT OFFICE.

CHRISTINA J. HIGLEY, OF NEW YORK, N. Y.

GARMENT-SUPPORTER.

SPECIFICATION forming part of Letters Patent No. 680,379, dated August 13, 1901.

Application filed June 8, 1900. Serial No. 19,608. (No model.)

To all whom it may concern:

Be it known that I, CHRISTINA J. HIGLEY, a citizen of the United States, residing at New York, in the county of New York and State 5 of New York, have invented certain new and useful Improvements in Garment-Supporters; and I do hereby declare the following to be a full, clear, and exact description of the invention, such as will enable others skilled in the 10 art to which it appertains to make and use the same.

My invention relates to improvements in garment-supporters, and particularly in stocking-supporters; and it consists in the novel 15 construction of the device.

The object of my invention is to overcome the tendency of that type of former stocking-supporters consisting of a pad adapted to be located over the abdomen and provided with 20 tapes, which may be attached to the stockings, to cause protrusion of the abdomen at the sides, so producing a tendency to hernia. This object is attained in the garment-supporter herein described, and illustrated in the 25 drawings which accompany and form a part of this application, in which—

Figure 1 is a front view of a female figure with my improved garment-supporter thereon, and Fig. 2 is a view showing the arrangement of abdominal muscles.

Stocking-supporters of the type above mentioned now in use and consisting of a pad provided with stocking-supporting tapes produce pressure against the strong and thick 35 sheath of the rectus-muscle. This portion of the abdomen is relatively firm and rigid, and pressure against it tends to produce bulging at the sides of the abdomen and in the vicinity of the external abdominal rings, at which 40 points the abdomen is weakest and at which points hernia takes place, if at all. The pressure upon the rectus-muscle and the consequent bulging in the neighborhood of the external abdominal rings necessarily increases 45 any tendency to hernia which may exist. Such tendency I seek to avoid by the use of a pad preferably formed of elastic material and which may be suspended in an elastic manner and the sides of which preferably 50 converge downwardly and in substantially the direction of the fibers of the external oblique muscles of the abdomen.

In Fig. 1, A is such a pad. B is a waist-belt, and C C are tapes by which the pad is suspended from the belt. D D are stocking-supporting tapes of the ordinary type, having bifurcated ends provided with clasps by which such ends may be connected to stockings.

Preferably the pad A is composed of flexible material, such as some woven flexible fabric, the edges being hemmed or otherwise reinforced to make them stiff and less yielding than the central portion. The suspension-tapes C may also be and preferably are 60 elastic, and the tapes D may also be elastic, if preferred. The shape of the pad and the location of the outer suspension-tapes C and the stocking-supporting tapes D in relation thereto are such that when the stocking-supporter is in use the lines of draft from the stockings to the belt (such lines being represented by the dotted lines E) are along or close to the outer edges of the pad and in substantially the direction of the external 70 oblique muscles. Substantially no pressure is exerted upon the central portion of the abdomen, therefore, by the pad A, the greater portion of the pressure being exerted along the outer edges of the pad, such pressure 75 tending not only to press back the abdomen as a whole, which is the particular advantage of this type of stocking-supporter, but to resist rather than to cause protrusion of the abdomen at such points, thereby avoiding 80 the objectionable action of former stocking-supporters of this type, as above mentioned.

Fig. 2 is a diagram showing the relative location of some of the principal abdominal muscles. F indicates one of the internal oblique muscles, G one of the external oblique muscles, and H the rectus-muscle, which is formed by interlacing fibers of the internal and external oblique muscles and of the transverse muscles beneath. The rectus-muscle 95 is strong and has a strong and thick sheath. As a result the central portion of the abdomen is far stronger than the side portions. It is against the central portion of the abdomen that pressure is exerted by former stocking-supporters of the type above mentioned, which are provided with a pad to be secured in front of the abdomen. Pressure against the central portion of the abdomen tends to produce 100

bulging at the sides, and particularly in the neighborhood of the crest of the ilium and of the inguinal canal, at which points the abdomen is especially weak. Bulging of the abdomen at these points tends to produce hernia or at least facilitates its production.

In the use of stocking-supporters of this class while the wearer is seated the stocking-supporting tapes are relaxed and the stockings tend to work downward because of the tension in their fibers. When the wearer again assumes a standing position, considerable strain is brought to bear upon the stocking-supporter by reason of the fact that the stockings have worked downward, and as such stocking-supporters have been constructed in the past the pad then exerts a considerable pressure upon the abdomen, which is disagreeable and which is or tends to be harmful. Such pressure is exerted very many times a day. My improved stocking-supporter herein described exerts no such pressure upon the central portion of the abdomen, the pressure that is exerted being distributed mainly in the vicinity of the edges of the pad and in the regions where the abdomen most requires support.

Because the pad acts at the sides rather than in the center, because of its yielding nature, and because of its elastic connection by the use of elastic tapes C to the supporting-belt B the pad is less prone to work out of place when in use than are the pads of for-

mer garment-supporters of this type and greater freedom of movement is permitted the wearer.

Having thus completely described my invention, what I claim, and desire to secure by Letters Patent, is—

1. In a garment-supporter, the combination, with a flexible abdominal pad, the sides of which converge downwardly, and which is provided with an elastic suspension device whereby it may be secured to the wearer, of stocking-supporting tapes secured to the lower portion of said pad. 40

2. In a garment-supporter, the combination, with an abdominal pad, the sides of which converge downwardly, and which is formed of flexible and elastic material, and is provided with an elastic suspension device whereby it may be secured to the wearer, of stocking-supporting tapes secured to the lower portion of said pad. 50

3. In a garment-supporter, the combination, with an abdominal pad formed of flexible material, of a waist-belt for supporting said pad, elastic material connecting said pad and waist-belt, and stocking-supporting tapes secured to the lower portion of said pad. 55

In testimony whereof I affix my signature in the presence of two witnesses.

CHRISTINA J. HIGLEY.
